UNITED STATES PATENT OFFICE.

WILLIAM A. JONES, OF TOLEDO, OHIO, ASSIGNOR OF ONE-HALF TO THE SWIGART OPTICAL COMPANY, OF SAME PLACE.

DESIGN FOR AN EYEGLASS-GUARD.

SPECIFICATION forming part of Design No. 35,093, dated September 17, 1901.

Application filed April 18, 1901. Serial No. 56,514. Term of patent 7 years.

To all whom it may concern:

Be it known that I, WILLIAM A. JONES, a citizen of the United States, residing at Toledo, Lucas county, Ohio, have invented and produced a new and original Design for Eye-glass-Guards, of which the following is a specification, reference being had to the accompanying drawing, forming part thereof.

The figure of the drawing illustrates an eyeglass-guard in perspective view, showing my design.

The leading or material feature of my design is a plate 1, having at the top a downwardly-inclined arm 2 and at the bottom a curved arm 3, projecting downwardly and outwardly at an angle thereto. The plate 1 has a series of adjusting-holes 4 disposed centrally and vertically of the body of the plate. At the extremities of the arms 2 and 3 are rigidly secured separate pad-plates 5. These plates are elongated rectangles in outline, and

their central longitudinal line is inclined at an angle to the central longitudinal line of plate 1. The bottom arm 3 of the flat plate 1, besides being curved, as described, is slightly bent out of a flat plane. The pad-plates 5 are disposed substantially in the same curved or bent plane as the plate 1.

It is apparent that this design is equally applicable to right-hand or left-hand guards.

Having described my invention, what I claim as new, and desire to secure by Letters Patent, is—

The design for an eyeglass-guard, as herein shown and described.

In testimony whereof I have signed my name to this specification in presence of two subscribing witnesses.

WILLIAM A. JONES.
